(57) **CLAIM**

The ornamental design for packaging for foodstuffs as shown and described.

DESCRIPTION

FIG. 1 is a top back perspective view of a packaging for foodstuffs showing my new design with the lid in a closed position and with the lid tabs in a first position;

FIG. 2 is a top back perspective view thereof with the lid tabs in a second position;

FIG. 3 is a top front right perspective view thereof;

FIG. 4 is a top, back, left perspective view thereof, shown with the lid in an open position;

FIG. 5 is a top, front, right perspective view thereof;

FIG. 6 is a bottom, front, right perspective view thereof, shown with the lid in a closed position; and,

FIG. 7 is a top view of the packaging for foodstuffs in an unfolded position.

The dot-dash-dot lines represent bend lines in the packaging for foodstuffs that form part of the claimed design.

1 Claim, 2 Drawing Sheets
